W. L. HERRING

SEESAW

Filed Sept. 12, 1925

UNITED STATES PATENT OFFICE.

WALTER L. HERRING, OF TULSA, OKLAHOMA.

SEESAW.

Application filed September 12, 1925. Serial No. 55,991.

This invention provides a toy for the amusement of children which admits of a child indulging in a teetering movement without requiring the assistance of a companion, as necessitated when indulging in the pastime of seesawing in the ordinary manner by means of a plank fulcrumed between its ends and requiring each end of the plank to be occupied.

10 The present invention contemplates a teeter member provided at one end with means for detachably connecting it to a suitable support, such as the jamb of a door frame, and having a seat at the opposite or free end 15 and equipped with a foot rest and a handle member, a counterbalancing spring being interposed between the teeter member and the support to which said member is pivoted.

The invention further contemplates novel 20 attaching means for the parts to admit of the toy being easily and quickly placed in position for use and readily dismounted to be laid aside when not required for immediate service.

25 While the drawings illustrate the preferred embodiment of the invention, nevertheless it is to be understood that in adapting the toy to meet different conditions the design may be varied and such other changes in the 30 minor details may be resorted to within the scope of the invention, as claimed, without departing from the spirit thereof.

For a clear understanding of the invention and the merits thereof reference is to be 35 had to the following description and the drawings hereto attached, in which,—

Figure 1 is a perspective view illustrating the toy in operative position.

Figure 2 is a fragmentary sectional view 40 through the teeter member, foot rest and standard forming the handle member, and

Figure 3 is an enlarged sectional detail on the line 3—3 of Figure 1.

Corresponding and like parts are referred 45 to in the following description and designated in the several views of the drawings by like reference characters.

The toy comprises a teeter member 1 which may be of any preferred material and which 50 is narrow for the greater part of its length and widened at one end to provide a seat 2 for reception of the child using the toy. An upright 3 projects from the member 1 adjacent the seat 2 and is provided at its upper 55 end with a cross piece constituting a handle bar 4. A suitable brace 5 supports the up-

right 3 and is interposed between it and the member 1. A foot rest is mounted upon the teeter member and, in the preferable construction, consists of a bar or like member 60 attached intermediate its ends to the member 1 by a fastening 7. Opposite ends of the bar 6 project laterally and incline outwardly and downwardly and terminate in offset portions 8 forming rests for the feet.

65 A counterbalancing spring 9 of the contractile type is connected at one end by means of an element 10 to the teeter member 1 and is adapted to be connected at its opposite end with the support to which the toy is attached. 70 A clamp 11 is provided as means for adjustably connecting the counterbalancing spring 9 to the support 12 and this clamp may be adjusted to vary the effective tension of the spring 9 according to the weight of 75 the child using the toy.

75 A clamp 13 similar to the clamp 11 is associated with the pivotal end of the teeter member 1 and serves as convenient means for pivotally, detachably and adjustably connecting the toy to the support. Each of the clamps comprises similar or like jaws 14, a connecting bolt 15 and winged nut 16, a spacing collar 17 being mounted upon the threaded end of the bolt and interposed between 80 the nut and the adjacent jaw. As shown, the spring 9 is connected to the bolt 15 of the upper clamp 11 and the teeter member 1 is pivotally connected to the bolt 15 of the lower clamp 13. A sleeve 18 connected to 85 the pivotal end of the member 1 receives the bolt 15 of the clamp 13.

90 When the toy is adjusted for use it is connected to a suitable support 12, as the jamb of a door, by means of the clamps 11 and 13, effective tension of the spring 9 being regulated by vertical adjustment of the clamp 11. The clamps are prevented from slipping by inwardly disposed points 17' 95 positively engaging the support, as indicated most clearly in Figure 3. The child perched upon the seat 2 grasps the handle bar 4 and may place the feet upon the rest 8 and by an upward impulse, such as in the act of seesawing, operates the toy in conjunction with the spring 9 in a manner to enjoy 100 a teetering movement.

105 Having thus described the invention, I claim:

110 1. A child's toy, comprising a teeter member, having a seat at one end, a clamp at the opposite end, embodying a pivot and clamp

bolt loosely engaging the member and having its ends projecting and jaws mounted on the projecting ends of the bolt, and a counter-balancing spring in cooperative relation with the said teeter member.

2. A child's toy, comprising a narrow teeter member having a seat at one end, a clamp at the opposite end of the member, embodying a bolt loosely connected thereto and having its ends extended and jaws mounted up-

on the projecting ends of the bolt, handle and foot rest members adjacent the seat end of the teeter member, a contractile spring connected at one end to the teeter member, a bolt at the opposite end of the spring, and jaws mounted on the ends of the bolt.

Signed at Tulsa, Oklahoma, this 11th day of January, 1926.

WALTER L. HERRING.
